UNITED STATES PATENT OFFICE.

GEORGE W. ORCUTT AND JAMES A. WOOD, OF LOS ANGELES, CALIFORNIA.

WINDMILL.

SPECIFICATION forming part of Letters Patent No. 309,645, dated December 23, 1884.

Application filed January 26, 1884. (No model.)

To all whom it may concern:

Be it known that we, GEORGE W. ORCUTT and JAMES A. WOOD, of Los Angeles, in the county of Los Angeles and State of California, 5 have invented a new and Improved Windmill, of which the following is a full, clear, and exact description.

The principal object of our invention is to provide a windmill of simple, inexpensive, 10 and durable construction, and which shall be self-regulating against variations of centrifugal force and wind-pressure.

The invention consists in the construction and arrangement of parts, as will be herein- 15 after described and claimed.

Reference is to be had to the accompanying drawings, forming a part of this specification, in which similar letters of reference indicate corresponding parts in all the figures.

20 Figure 1 is a central vertical sectional elevation of our improved windmill, showing the connections for driving a well-pump. Fig. 2 is a plan view of the same, and Fig. 3 is a horizontal sectional view on line $x'x'$, Fig. 1.

25 The letter a indicates a substantial frame or tower, in which the wind-wheel of the mill is journaled by its central post, b , at c in a top cross-bar and at d in a strong sill-timber, as shown. We make the center post or vertical axis, b , of the wheel in square or angular cross-sectional form, to afford a bearing for the parts of the wheel mounted on the post and which are to turn with the post.

30 The wind-wheel consists, mainly, of upper and lower frames, $e f$, made preferably in circular form, and fitted on the post b , and having the fans, sails, or wings g pivoted at their outer edges between the frames on the rods or bars h . The inner or free edges of the fans g are 35 connected by strong rods i with a central frame or wheel, j , which we call the "governor" of the mill. The governor j has loose bearings 40 on the post b , so as to slide up and down freely on the post as the wind-wheel revolves.

45 Rising from the governor j , and fixed to the same at their lower ends, are two rods or bars, k , which are preferably bent inward toward each other at l , and carry fixedly at their tops the horizontal ring plate or disk m , which 50 rises and falls with the governor.

On a cross-bar of the frame a we pivot or fulcrum at n a swing-frame of parallel bars o , having anti-friction rollers p journaled thereon directly below the disk m , and extending outward to the side of frame a , where said bars o are connected by a cross-bar, r , to which is connected a cord, rope, or chain, s , passing upward over a sheave or pulley, t , and then downward through any suitable guide-staples within reach of the attendant, so that by drawing on rope s the rollers p will be raised 55 against the revolving disk m to raise it and lift the governor j , and cause the rods i to close the fans or wings g of the wheel when the mill is to be stopped, and when the mill is to run 60 the rope s is unfastened to let the frame-bars o drop against a cross-bar of frame a , or any suitable stop, to allow fans g fully to open, in which position the inner or free edges of the fans rest against the periphery of the governor j , as shown. 65

The action of the wind-wheel is as follows: The wind striking the concave faces of the fans g will cause the wheel to revolve, and when the speed reaches a certain limit the centrifugal force will act to close the fans independently of the action of the wind thereon. The fans in closing lift the governor j by the rods i , and by weighting the governor more or less the speed of the wheel may be controlled. 70 Any overpressure by an increased wind force 75 also tends to partly close the fans and lift the governor, and the mill will continue to run at an even speed in violent wind-storms. The speed of the wheel is determined wholly by the 80 velocity, any tendency to excess of speed acting through the governor to partially close the fans, and when the wind force decreases the weight of the falling governor will gradually open and hold the fans, to maintain the 85 uniform speed for which the governor is set. It will thus be seen that by a very simple construction and arrangement of parts we provide a wind-wheel which closely regulates itself as to speed against variation of centrifugal force 90 incident to the connection or disconnection of any of the machinery which may be driven by the mill, and also against variations of wind force. By pivoting the fans g at their outer edges the wind has a driving effect on the wheel 95 100

as it leaves the wheel as well as on entering the wheel.

The mill is stopped by drawing upon and securing the rope *s*, as above described. The 5 lower step-bearing, *d*, only requires oil, which may be supplied to it by an oil-cup, *u*, one filling of which will last for a long time.

Power may be taken from the wheel-shaft *b* by any system of wheel or belt gearing for 10 driving general machinery; but we have devised a simple plan for giving motion to the working-lever *v* of a rod, *w*, working a pump in a well, *x*, for which purpose we connect to the shaft *b*, one over the other, a couple of 15 shafts or axles, *a'*, on which revolve freely the anti-friction wheels *b'*, which as the shaft turns act on opposite sides of a plate or disk, *c'*, fitted loosely around and free from the shaft, and fixed rigidly to the lever *v* at *d'* in oblique position, so that the rotation of the shaft causes 20 a rocking of lever *v* on its fulcrum *c'*, to work the well-pump. The action of the wheels *b'* and disk *c'* is positive and noiseless, and the power is taken to work the pump very near 25 the shaft *b*, and lateral strain upon the shaft-bearings and on the mill-frame is thereby avoided.

The movements of the lever *v*, its disk *c'*, and the wheels *b'* are clearly indicated in full and 30 dotted lines in Fig. 1.

We propose to make the fans *g* of sheet metal and coat them with weather-proof paint to insure durability.

Having thus described our invention, we claim as new and desire to secure by Letters 35 Patent—

1. In a windmill, the combination, with the pivoted fans *g*, governor *j*, and rods *i*, connecting the fans with the governor, of the rods *k*, disk or plate *m*, swing-frame bars *o*, having 40 anti-friction rollers *p*, and the rope or chain *s*, arranged for lifting the governor to close the fans and stop the wind-wheel, substantially as shown and described.

2. The combination, with the wind-wheel 45 shaft *b*, provided with the two axles *a'a'*—one above the other—and rollers *b'b'* thereon, of the pivoted lever *v*, provided at its inner end with the inclined centrally-perforated disk *c'*, said disk passing loosely around the shaft *b* 50 and between the two friction-rollers, whereby when the wind-wheel shaft is rotated the lever *v* will be positively operated both in its upward and downward movement, substantially as set forth.

GEO. W. ORCUTT.
JAMES A. WOOD.
